UNITED STATES PATENT OFFICE.

OTTO BRUNO FRIEDEL, OF OBERSACHSENBERG, GERMANY.

MUSICAL INSTRUMENT.

Application filed March 17, 1926, Serial No. 95,444, and in Germany April 20, 1925.

My invention relates to musical instruments and more particularly to reed instruments, for instance, to mouth organs in which a variation of the pitch is effected by 5 adjusting two reed plate slides.

It is an object of my invention to provide an instrument of the kind described in which the various pitches, octave, third, and fifth, may be played with full accords and the 10 lower row of tones may be fully utilized with the corresponding pitches under all conditions.

To this end, I provide in one of the reed plate slides, and preferably the upper one, 15 cells for four high tones more than in the other slide.

In a preferred construction, one of the slides, for instance, the lower one, is provided with a row of cells for higher half 20 tones, and a row of cells for lower half tones, at the right and at the left of its row of full-tone cells, so that all half tones are provided for each pitch and the player is enabled to play any tune chromatically.

25 In the drawings, two types of mouth organs embodying my invention are illustrated by way of example.

Figs. 1 to 6 illustrate the above-mentioned preferred construction with half-tone cells, 30 Figs. 7 to 14 illustrate a type without such cells, and

Figs. 15, 16 and 17 are diagrams showing various positions of the reed plate slides for the preferred construction.

35 More particularly

Fig. 1 is an elevation,

Fig. 2 is a perspective view of the organ,

Fig. 3 is a perspective view of its reed plate slides,

40 Fig. 4 is an end elevation of the organ,

Fig. 5 is a cross section on the line V—V

in Fig. 1,

Fig. 6 is a section similar to Fig. 5, the parts adjacent the section being shown in 45 perspective,

Fig. 7 is a perspective illustration of the type without half-tones,

Figs. 8 and 9 are longitudinal sections of the organ, showing its slides in two different 50 positions,

Fig. 10 is a plan view of the right-hand end of the organ,

Fig. 11 is an end elevation of this end,

55 Figs. 12, 13 and 14 are cross sections on the lines A—B, C—D and E—F in Fig. 8.

Referring now to Figs. 1 to 6, the organ

comprises two reed plate slides *a* and *b* in which cells for the reeds are formed, for instance by milling, reed plates *c* and *d* secured to the top of the upper slide *b* and the 60 bottom of the lower slide *a*, and a casing *e* which is secured to the end and rear edges of the lower slide *a*. The front edge of the casing is the mouth piece of the organ and is provided with holes conforming to 65 the cells of the two slides. To prevent jamming of the player's tongue in the holes of the mouth piece, a moisture-proof lining *g* is inserted at the rear of the mouth piece and provided with corresponding holes. 70

The upper reed plate slide *b* is adapted to be displaced on lower one to which the casing *e* is secured, by means of a handle *h*, and slide bars *f* are formed along the longitudinal edges of the casing *e* to guide the 75 slide *b* when it is being so displaced. The upper slide *b* has four high tones more than the central row of tones in the lower or stationary slide *a* and the distance which the upper slide may be displaced is equal to the 80 space of the four cells which correspond to the additional tones.

To enable the player to find the desired position of the upper slide *b* on the lower slide *a*, readily and without experimenting, 85 a spring catch *i* is provided on the top of the slide and adapted to co-operate with three recesses *O*, *T* and *F* in the top plate of the casing *e*. In the normal position of the slide *b*, that is, the octave position, the 90 spring *i* is in the recess *O*. When it is desired to play the third or fifth pitch, the slide *b* is displaced to the left by its handle *h* until the spring *i* is arrested by one of the other recesses, *T* or *F*, as the case may be. 95

For chromatic playing, seven half tones are provided on the right, and eight half tones on the left, of the full tone row of the lower slide which are sounded by the player as desired. The number of the half tones 100 is not limited to seven and eight but is a function of the number of the full tones.

Referring now to Figs. 7 to 14, these show the type without half-tones. The two reed plate slides 1 and 2 are connected by dovetailed slide bars and are free to be adjusted between checks 3. A cover 6 and a cover 7 which may be of any suitable shape, are secured to the slides 6 and 7, respectively. A handle 8 serves for adjusting the upper 105 slide. To enable the player to find the desired position for a given pitch, a spring 9

is provided on the upper slide 2 and adapted to cooperate with notches *o*, *t* and *f* in a plate 10 at the lower slide 1, similarly as described with reference to Figs. 1 to 6.

- 5 To prevent jamming of the player's tongue in the holes, a lining 12 is secured to the rear of a plate 12 which is fastened to the lower slide 1, holes being formed in the plate and the lining.
- 10 It will be understood that any number of tones may be provided and the size will vary in proportion.

In mouth organs of the usual type, only a single pitch is available and generally organs are designed for either the octave or the third pitch, as these are the most popular with players. By providing two adjustable slides as described, and arranging the tone cells as described, I am enabled to design 20 the same instrument for three pitches, the octave, the third, and the fifth, and to vary the pitch while playing.

The operation of both types is the same. The fundamental pitch is the octave. In the diagrams Figs. 15, 16, and 17, the arrangement of the holes in the mouthpiece for the full tones, central row, and the half tones, rows at each side of central row in the lower slide, are indicated and designated by "3" 30 and "8", respectively, for the tones produced by blowing and those produced by suction.

A diagram for the second type would be quite similar but obviously without the half tones.

35 In Fig. 15, the two slides *a* and *b* are in the normal or octave position in which the four additional holes of the upper slide are inoperative. For the third pitch, the upper slide is moved two holes to the left, as shown 40 in Fig. 16, and the organ is now similar to a normal organ for third pitch, and for the fifth pitch, the upper slide is moved two more holes to the left.

It will be understood that the "effect" of 45 the play may be much enhanced by varying the pitch as described, and that it is possible to obtain the same performance with a single instrument as with three separate instruments of the usual construction.

50 Both types may have mouth pieces on either side, and their size, as mentioned, is obviously a function of the number of tones provided, but in any case the upper reed plate has four tones more than the lower one, 55 or vice versa.

My invention is not limited to mouth organs but may be applied to any other reed instruments, for instance, accordions.

I claim:

- 60 1. Musical instrument comprising two reed plate slides, means for adjusting said slides with regard to each other, each slide having tone cells, and one of said slides having four cells more than the other.
- 65 2. Musical instrument comprising two reed

plate slides, means for adjusting said slides with regard to each other, one of said slides having a set of full tone cells and sets of half tone cells at either side of said row, and the other slide having four more tone cells than the full tone row of said other slide.

3. Musical instrument comprising two reed plate slides, means for adjusting said slides with regard to each other, a casing surrounding both slides and secured to one of them, and slide bars for the other slide formed in said casing, each slide having tone cells, and one of said slides having four cells more than the other.

4. Musical instrument comprising two reed plate slides, means for adjusting said slides with regard to each other, and checks on said slides for limiting their adjustment, each slide having tone cells, and one of said slides having four cells more than the other.

5. Musical instrument comprising two reed plate slides, means for adjusting said slides with regard to each other, and means for indicating the relative position of said slides, each slide having tone cells, and one of said slides having four cells more than the other.

6. Musical instrument comprising two reed plate slides, means for adjusting said slides with regard to each other, and a spring catch for indicating the relative position of said slides, each slide having tone cells, and one of said slides having four cells more than the other.

7. Musical instrument comprising two reed plate slides, means for adjusting said slides with regard to each other, a casing surrounding both slides and secured to one of them, said casing having recesses, and a spring catch on one of said slides which is adapted to engage said recesses, each slide having tone cells, and one of said slides having four cells more than the other.

8. Musical instrument comprising two reed plate slides, means for adjusting said slides with regard to each other, a casing surrounding both slides and secured to one of them, said casing having a recess for each pitch to be played on said instrument, and a spring catch on one of said slides which is adapted to engage said recesses, each slide having tone cells, and one of said slides having four cells more than the other.

9. Musical instrument comprising two reed plate slides, means for adjusting said slides with regard to each other, a spring catch on one of said slides, and a notched plate on the other slide which is adapted to cooperate with said catch, each slide having tone cells, and one of said slides having four cells more than the other.

10. Musical instrument comprising two reed plate slides, means for adjusting said slides with regard to each other, each slide having tone cells, and one of said slides having four more tone cells than the other, a

mouth piece having holes adapted to register with said tone cells, and a lining of waterproof material at the rear of said mouth piece.

5. 11. Musical instrument comprising two reed plate slides, means for adjusting said slides with regard to each other, each slide

having tone cells, and one of said slides having more tone cells than the other.

In testimony whereof, I have signed my name to this specification at Dresden this 23rd day of February, 1926.

OTTO BRUNO FRIEDEL.
